PROPELLER TYPE DRIVE

Charles A. Le Bert, Evangeline, La., assignor of
one-half to Carroll V. Radke, Jennings, La.

Application April 21, 1943, Serial No. 483,935

1 Claim. (Cl. 115—34)

This invention relates to a propeller type drive for boats and the primary object of the invention is the provision of a device of the stated character which will provide several propelling speeds forwardly and reversely and provide a neutral position through the use of a propeller wherein the pitch of the blades thereof may be varied and an operating means for varying the pitch of the blades at the will of the operator.

Another object of the invention is the provision of a device of the above stated character which may be easily installed in a boat and its construction is such, that the control may be located within the boat within convenient reach of the operator and the connection thereof with the blades of the propeller be enclosed within the propeller shaft and protected thereby. Also the construction will prevent water from entering the boat through and about the propeller shaft.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation, partly in section, illustrating a propeller type drive for a boat.

Figure 2 is a fragmentary vertical sectional view illustrating a portion of the propeller shaft and showing the mounting of the propeller blades thereon.

Figure 3 is a fragmentary longitudinal sectional view showing a portion of the operating means for varying the pitch of the blades of the propeller.

Figure 4 is a fragmentary sectional view illustrating the propeller hub and the connection of the propeller blades with a control shaft.

Referring in detail to the drawing, the numeral 5 indicates a fragmentary portion of a boat, 6 the propeller shaft bearing which permits the propeller shaft to extend through the keel of the boat and is of the type to prevent leakage between the keel and the propeller shaft. The bearing 6 includes in its construction a stuffing gland 7 which may be adjusted and repacked from the interior of the boat.

A tubular propeller shaft 8 is journaled in the bearing 6 and is also supported by a thrust type bearing 9 mounted within the boat. The outer end of the propeller shaft is provided with

5 external threads on which a hollow hub 10 of a propeller 11 is threaded. A suitable lock nut 12 threads on the propeller shaft 8 against the threaded neck of the hub 10. The hub 10 is provided with oppositely arranged tubular bearings 13 in the form of sleeves secured to the hub in such a way as to exclude water from the interior of the hub. The bearings 13 extend exteriorly of the hub to receive shanks 14 of propeller blades 15. The bearings 13 also include stuffing glands 16 to prevent water from seeping between the shanks of the blades 15 and the bearings.

10 The inner ends of the shanks 14 within the hub are spaced and provided with ears 17 to which links 18 are pivoted. The links are pivotally connected to an operating shaft 19 extending into the propeller shaft and which carries at its innermost end a key or pin 20 which extends through slots 21 provided in the propeller shaft 8.

15 Surrounding the propeller shaft and the slots 21 thereof is a housing 22. The housing has a sliding fit with the propeller shaft 8 and rests 25 against a block 23 fixed in the boat so that the housing will not rotate with the propeller shaft. The key or pin 20 has fixed to its ends bearing 20 elements 24 which bear against discs 25 arranged within the housing and surrounding

20 the propeller shaft. The discs 25 act to take wear and provide bearing connection between the elements 24 and the housing, permitting the key to rotate with the propeller shaft while the housing is non-rotatable. Ears 26 are formed on opposite sides of the housing and have pivoted thereto links 27. The links are pivotally connected to a fork portion 28 of a control lever 29 pivotally mounted, as shown at 30, within the boat. The control lever 29 is provided with a

35 detent 31 which operates in conjunction with a quadrant 32 mounted in the boat providing a construction which will permit the control lever to be releasably secured in several positions. By 40 adjusting the control lever in one direction the pitch of the propeller may be varied to give high and low speeds in a forward direction and the adjustment of the control lever in an opposite direction beyond a neutral position will vary the pitch of the blade so as to give a reverse driving action to the boat at several speeds.

45 As the water is excluded from the interior of the hub secured on the end of the tubular propeller shaft 8, it will not be possible for the water to work its way into the boat by way of the propeller shaft and it will be seen that the operating

shaft and its connection with the propeller blades is entirely confined within the propeller shaft, permitting the installation of the device to the boat to be easily carried out and that the operating shaft and connecting links with the propeller blades are entirely protected by the propeller shaft and the hub of the propeller.

While I have shown and described the preferred embodiment of my invention, it will be understood that minor changes in construction, combination and arrangement of parts may be made without departing from the spirit and scope of the invention claimed.

Having thus described my invention, what I claim is:

In a propeller type drive for boats, a propeller shaft bearing mounted in a hull of a boat, a hollow propeller shaft supported by said bearing, a

propeller including a hollow hub detachably secured to said shaft and blades journaled in said hub to permit the pitch thereof to be varied, an operating means located in the boat, an operating shaft lying within the propeller shaft and hub, links connecting said operating shaft with the blades, said propeller shaft having slots, a pin secured to the operating shaft and extending through the slots, a housing slideable on the propeller shaft over the slots, bearing elements secured to the pin, wear plates between the housing and the bearing elements, a bearing block engaged by the housing and secured to the boat for retaining the housing against rotation with the propeller shaft and permitting the housing to slide relative to the propeller shaft, and means connecting the housing to the operating means.

CHARLES A. LE BERT.
